FOREIGN PATENT DOCUMENTS

JP 2020052069 A * 4/2020

Primary Examiner — R. Johnson(74) *Attorney, Agent, or Firm* — Dunlap Bennett & Ludwig, PLLC(57) **CLAIM**

The ornamental design for a guitar body, as shown and described.

DESCRIPTION

FIG. 1 is a front perspective view of the guitar body, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is another front perspective view thereof, shown in use with a fully shown neck and headstock.

The broken lines shown in the drawings depict portions of an electric guitar that forms no part of the claimed design.

1 Claim, 6 Drawing Sheets(56)
